(57) **CLAIM**

The ornamental design for a robot children's vehicle, as shown and described.

DESCRIPTION

FIG. 1 is a first perspective view of a robot children's vehicle showing my new design;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof;

FIG. 9 is an enlarged view of the selected portion 9 in FIG. 1;

FIG. 10 is an enlarged view of the selected portion 10 in FIG. 1; and,

FIG. 11 is an enlarged view of the selected portion 11 in FIG. 2.

The dash-dot broken lines are included to show enlarged partial views in FIGS. 1, 2 and 9-11. All other broken lines represent portions of the robot children's vehicle that for no part of the claimed design. None of the broken lines form a part of the claim.
